UNITED STATES PATENT OFFICE.

GEORGE H. PERKINS, OF PHILADELPHIA, PENNSYLVANIA.

APPARATUS FOR SEPARATING AND DISTRIBUTING DISTILLATES.

SPECIFICATION forming part of Letters Patent No. 314,715, dated March 31, 1885.

Application filed May 2, 1884. (No model.)

To all whom it may concern:

Be it known that I, GEORGE H. PERKINS, a citizen of the United States, residing in the city and county of Philadelphia and State of 5 Pennsylvania, have invented an Improved Apparatus for Separating and Distributing Distillates and Kindred Products, of which the following is a specification.

My invention is especially designed for use 10 in oil-refineries, although it is capable of many applications in the arts, which will be obvious when its construction is understood, and which it is not necessary to mention here. When crude oil is charged to and heated in a still, 15 its vapors are conducted through a pipe leading from the dome of the still and immersed in water. In practice this vapor-pipe is made so long that it is usually in the form of a worm coiled within a vessel containing the water, 20 and of such extent that the vapors are thoroughly condensed in passing through it, and run from its discharging extremity as a liquid or distillate. The first liquid that comes from the pipe is, in common refinery parlance, 25 called "light benzine," the next "heavy benzine," the next "standard white oil" of a given specific gravity, the next again "water white oil" of another gravity, and still the next "standard white oil" of yet another 30 gravity, and so on through a series of gravities until the charge in the still has been completely vaporized or reduced to tar and coke. As distillates of different gravities are refined into separate marketable products, and as they 35 are produced in series, so to speak, continuously in the same apparatus and from the same original charge, it becomes of great importance to separate them accurately and receive the different varieties in separate and distinct 40 vessels, so that distillates of different gravities and colors shall not become commingled.

Heretofore, as is well known to those familiar 45 with the refining of oil, many contrivances have been resorted to for securing the accurate separation and distribution of the different distillates successively; but all of these contrivances have been imperfect, in that they either failed to successively secure the desired separation or were of such form of construction as to be dangerous in practical use.

The object of my invention is the construction of an apparatus for securing the accurate

separation and separate successive distribution of distillates of different gravities and colors.

To the above ends my invention consists in a distributing apparatus, a preferred type of a convenient embodiment of which is herein-after described and claimed.

In the accompanying drawings, the first six figures of which represent a good form of a convenient apparatus embodying my invention, and in which Figure 7 represents a slightly modified form also embodying my invention, Fig. 1 is a top plan view of the entire device. Fig. 2 is a top plan view of the inclosed casing, with the cover-plate and pan removed. Fig. 3 is a vertical central sectional elevation through the entire apparatus, indicating the position which the pan-outlet occupies when it is aligned with one of the distributing-pipes. Fig. 4 is a similar view of the pan removed from the casing. Fig. 5 is a top plan view of the pan removed from the casing. Fig. 6 is a side elevational detail of the handle, and Fig. 7 a view similar to Fig. 3, representing a construction in which the pan proper is replaced by a curved rotatable pipe which operates in essentially the same manner that the pan operates and to the same result, all as hereinafter more fully explained.

Similar letters of reference indicate corresponding parts.

Referring now to the first six figures of the drawings, A represents a casing, preferably 85 cylindriform, and inclosed by an accurately-fitting cover-plate, B. Into the upper portion of the casing opens and discharges the distillate-pipe C, which leads from the still, in proximity to said still is known as the "vapor-pipe," and in which the vapors are condensed. Fitted within the upper portion of the casing conveniently by means of the pivot-standard 90 a is a rotatable pan, D, of circular outline, which is adapted to be rotated within the casing. Rotation of this pan is conveniently effected through the instrumentality of a vertical stem, d, which is affixed to the pan, or, more conveniently, to a vertical boss, d', formed therein or attached thereto, and which is in alignment with the pivot with respect to which the pan rotates. The stem passes through a stuffing-box, b, applied to the cover-plate and forming a bearing for said stem, and is itself

conveniently rotated by a pivoted handle, E, as shown. The pan is, near its circumference, provided with an aperture through its bottom, which I term a "pan-outlet," $\hat{d}$, and which 5 is simply a preferably circular opening. This pan-outlet is surrounded or bounded as to its under edges by a small depending rim or flange, as shown in the drawings, the office of which is to prevent the crawling of the dis- 10 charging-liquid over the bottom of the pan and its dribbling thence into the casing. Arranged in circular series, and at a similar radial dis- 15 tance from the vertical axis of the casing, are a given number of distributing-pipes, F, which exist within the casing as upright open-topped pipes, most conveniently pass through the base of the casing, and then branch off laterally to the receiving-vessels in which the different distillates are designed to be ultimately dis- 20 charged. Exterior to the casing each of these pipes is provided with a valve, (not shown in drawings,) by which the flow through said pipes can be stopped or regulated at will, so that communication can be cut off at will, this 25 feature being valuable in case of a fire in the works. The open upper extremities of these pipes are conveniently of a diameter greater than that of the pan-outlet, and their arrange- 30 ment is such that upon the rotation of the pan its outlet can be successively caused to regis- 35 ter over the open upper extremity of each of said pipes, as will be clearly understood by reference to Fig. 3.

S, Fig. 2, represents a hole in the bottom of the casing, to which is attached what is known as a "slop-line," which is not shown in the drawings, but which is simply a distributing-pipe similar to the distributing-pipes F, with this exception, that it has no extension up into 40 the casing. The office of the slop-line is hereinafter more fully explained. The cover-plate is conveniently provided with a circumferential downwardly-depending flange, b', which registers accurately within the chine or top opening of the pan. The vapor-pipe opens within the line of this depending flange, which latter is for the purpose of preventing any distillate that may condense on the under side of the cover-plate from running over outside of 45 the pan. The flange returns them to the inside of the pan.

As a means of determining the position of the pan-outlet with respect to any particular distributing-pipe or with respect to the slop-line, so as to cause the accurate alignment of said outlet with respect to any particular pipe, the cover-plate is provided with a series of pairs of vertical stops, G, between any pair of which the handle can be caused to drop, and 50 can be, if desired, locked by a pin, g, so that any accidental rotation of the handle, and consequently of the pan with which it is connected, is prevented. The stops shown are simply the most convenient devices of which 55 I have knowledge for effecting the purpose above named; but, as will be readily under-

stood, other stopping or locking devices may be substituted in their stead. In fact, the handle as such may be dispensed with and a hand-wheel, gear-wheel, or other suitable actuating 70 device for the pan be substituted in its stead. In connection with each pair of stops, and as a means of indicating with which particular distributing-pipe the pan-outlet is caused to correspond when the handle is locked with respect to any particular pair of stops, the distributing-pipes are numbered, and finger-indices I in the form of flanges, containing a given number of perforations visible by day, and which may be detected by the sense of 80 touch when the apparatus is in use at night, are applied to the cover-plate, as represented in the drawings.

Other devices—such as numbers or pins—may be substituted in the stead of the finger- 85 indices referred to, although I consider the latter the best devices for the purpose.

J is a gas-outlet opening from the cover-plate, as shown in Fig. 1, provided for the escape of such fixed gases as will not condense 90 in an ordinary worm or condenser.

K is a removable plate, of glass, or, if desired, of metal, which covers a man-hole, through which scale and dirt in the pan can be removed and the interior of the pan in- 95 spected without removing the cover B.

The casing, pan, and cover-plate are of such mechanical construction as convenience of manufacture may dictate, and the casing is supported in any desired manner. It is not 100 necessary that the distributing-pipes should pass out through the bottom of the casing, as they may pass through its side walls. The cover-plate is securely applied to the casing after the pan is in place. The pan itself is 105 formed with an overhanging inturned edge, e, to prevent any possible escape of distillate.

The operation of the device has been already sufficiently set forth in connection with the description of the construction. Suffice it 110 to say that when the pan is locked in a given position with respect to any distributing-pipe, distillate fed into it can discharge through but one distributing-pipe, so that it is impossible for a distillate of a given gravity to become 115 commingled with a distillate of a different gravity, the pan being locked so as to cause the alignment of its opening with that distributing-pipe only which leads to the receiving tank for the particular distillate for 120 the time being fed. When the still runs a quality of distillate requiring redistillation, and not proper to be received through any of the regular distributing pipes or lines, as may occur when the fire gets too hot, the 125 pan is shifted so that its outlet is aligned over the opening of the slop-line, and the distillate run off through said slop-line. The same set of the pan is resorted to when, as is usual before starting the still, water is put through 130 the worm, the water being run off through said slop-lines. Again, the slop-line is em-

ployed when an obstruction occurs of such character as to dam up any particular distributing-pipe and to cause the backing up of the liquid in said pipe and its overflow 5 from the extended top thereof into the casing, in which event the overflowed liquid simply runs off through the slop-line and cannot enter any of the other distributing-lines.

The valves in the various distributing-pipes 10 are always all kept closed, except the one into which the pan is for the time being emptying, and except the valve in the slop-line. This is necessary, because the distillate, when passing through the apparatus, is hot and throwing off more or less gas, which would communicate to the other pipes, and, condensing to the extent of the condensed liquid, mix the products. The valves, however, are principally employed as a safeguard against conflagration and to prevent fire from communicating from one line or tank to another. They are, therefore, safety appliances rather than anything else, although, as stated, they 15 perform a good office in preventing the gases of one distillate from mixing and condensing with the gases of another distillate in another line. The closed casing around the pan prevents the escape of gases except through the gas-outlets provided for the purpose, which 20 leads to a safe distance and delivers the gas for utilization. By this arrangement all danger from fire is avoided.

In the modified form of construction represented in Fig. 7 the distillate-pipe C is arranged to open and discharge centrally with 25 respect to the cover-plate of the casing and into a crooked pipe, Q, which is adapted by means of a rotatable stem, q, upon which said pipe is suspended, and which passes up through a bearing or stuffing-box in the vapor-pipe, to 30 be rotated with respect to the various distributing-pipes F, so that its discharging-nozzle can be held with respect to any one of said distributing-pipes in the same manner that 35 the pan-outlet of the pan can be. The crooked pipe is adapted to be rotated by means of a pivoted handle, E, connected with the stem q, and adapted to be operated and secured in given positions, as in the case of the handle 40 heretofore described with respect to the rotatable pan D. This arrangement is essentially 45 a mechanical equivalent for the pan described, and differs from it in no respect as to its mode of operation. A gas-outlet, J, is represented 50 in this figure as applied to the cover-plate of the casing. If desired, however, the gas-outlet 55 may be arranged to branch out from the distillate-pipe, the discharging-orifice of which latter is arranged to open within the receiving-throat of the crooked pipe Q, as shown in the drawings.

The proportions of the casing in the modified construction of Fig. 7 are somewhat different from the proportions represented in 60 the other figures; but these proportions may be modified, as any mechanic will understand,

without affecting either the principle or the mode of operation of the invention.

To sum up: The crooked pipe is essentially the equivalent of the pan provided with the outlet, the receiving-throat of said pipe performing the office of the pan in receiving the distillates, and its discharging-orifice performing the office of the pan-outlet in discharging the received distillate into any given 75 distributing-pipe.

Having thus described my invention, I claim—

1. In combination with an inclosed casing provided with distributing-pipes, a rotatable 80 pan provided with an outlet adapted upon the rotation of the pan to register with respect to any given distributing-pipe, substantially as set forth.

2. In combination with an inclosed casing 85 provided with distributing-pipes and a slop-line pipe, a rotatable pan provided with an outlet adapted upon the rotation of the pan to register with respect to any given distributing-pipe.

3. In combination with an inclosed casing 90 provided with distributing-pipes, a rotatable pan provided with an outlet adapted upon the rotation of the pan to register with respect to any given distributing-pipe, and means for 95 causing the rotation of the pan, substantially as set forth.

4. In combination with an inclosed casing provided with distributing-pipes, a rotatable 100 pan provided with an outlet adapted upon the rotation of the pan to register with respect to any given distributing-pipe, means for causing the rotation of the pan, and means for securing the pan fixedly in given positions, substantially as set forth.

5. In combination with an inclosed casing 105 provided with distributing-pipes, a distillate-inlet pipe and a gas-outlet, a rotatable pan provided with an outlet adapted to register with any one of the distributing-pipes into 110 which pan said distillate-pipe discharges, substantially as set forth.

6. In combination with an inclosed casing 115 provided with distributing-pipes and a slop-line pipe, a rotatable pan provided with an outlet adapted to register with any one of the distributing-pipes or with the slop-line pipe, into which pan said distillate-pipe discharges, substantially as set forth.

7. In combination with an inclosed casing 120 provided with distributing-pipes, a distillate-inlet pipe and a gas-outlet, a rotatable pan provided with an outlet adapted to register with any one of the distributing-pipes, into 125 which pan said distillate-pipe discharges, and means for rotating the pan, substantially as set forth.

8. In combination with an inclosed casing 130 provided with distributing-pipes, a distillate-inlet pipe and a gas-outlet, a rotatable pan provided with an outlet adapted to register with any one of the distributing-pipes into

which pan said distillate-pipe discharges, means for rotating the pan, and means for locking the pan in different positions, substantially as set forth.

5 9. In combination with the inclosed casing, the rotatable pan, the handle and stops, and the finger-indices, substantially as set forth.

10. The combination of the casing having a cover-plate provided with a depending

flange, b' , and the rotatable pan provided with 10 the inturned edge e , substantially as and for the purposes set forth.

In testimony whereof I have hereunto signed my name this 29th day of April, A. D. 1884.

GEORGE H. PERKINS.

In presence of—

C. B. TAYLOR,

J. BONSALL TAYLOR.
